METHOD OF APPLYING TUBULAR RIVETS

Harold C. Sundstrom, Chicago, Ill.

Application May 26, 1943, Serial No. 488,553

1 Claim. (Cl. 218—29)

This invention relates to rivets and more particularly to an improved tubular rivet and a novel method of applying rivets of that general character to articles desired to be joined together.

The present invention is particularly adapted to overcome the deficiencies of the various forms of known rivets and the existing unsatisfactory methods of applying the same which have resulted in the formation of imperfect unions between riveted articles. Heretofore, when it was desired to fasten together two articles by the use of a hollow, tubular rivet, the rivet was first inserted in the preformed aligned openings of the articles after which pressure was brought against the ends of the rivet by various means so as to upset at least one end thereof. As a result the articles were confined between the upset portion and the other retaining end of the rivet. Although a union between the articles was effected to some degree in that the two articles were held together in such a manner that they could not be entirely separated one from the other, nevertheless the effected union was imperfect and not a tight positive one whereby the articles would be incapable of relative movement in any and all directions. In such unsatisfactory unions, the articles were still capable of a slight amount of relative movement in various directions and particularly relative twisting or rotative movement with respect to each other about the rivet as a pivot point. These loose unions were especially undesirable where the articles were subjected to substantial vibration, twisting stresses and other strains during normal use or operation of the structure of which the articles were parts. Also it was found that upon upsetting hollow rivets having a closed head end portion, the central portion of the head end collapsed or became distorted or depressed with the result that an irregular head having an irregular retaining flange was produced which collected dirt, increased wind resistance, and had other disadvantages.

The same general problem and failure to achieve unions between articles that were tight, positive and satisfactory in all respects has existed also in the use of solid rivets. It has been recognized that one of the principal reasons for such imperfect and loose rivet unions is the fact that the shank of the rivet, which normally is of such dimension as to permit its ready insertion into the preformed openings of the article to be riveted together, fails to tightly engage the vertical side walls of the preformed openings upon the rivet's being upset by the old well-known methods to fastening position. The slight clear-

ance space which facilitates ready insertion of the rivet into the preformed openings is not taken up by the rivet when it is upset and, consequently, slight relative movement between the articles is permitted.

To overcome the foregoing difficulties and deficiencies, various efforts have been made by skilled workers in the art. These efforts, however, prior to my invention, had been proven failures or had been rewarded with only partial success, leaving the problem as yet unsolved. One attempted solution has been by the well-known method in use today which comprises first cooling or reducing the rivet to a very low degree of temperature so as to shrink its overall dimensions and then applying the rivet when still cold into the preformed openings of the articles to be riveted, the openings being slightly larger than the reduced dimension of the cold rivet.

10 The underlying theory of this cold method is that the rivet upon returning to its normal temperature would expand to its normal size and, thereby, into a snug, tight engagement with the sides of the preformed openings. However, this 15 cold method has not been found satisfactory since the shrinkage of the rivets by cooling is relatively inconsequential and insufficient to achieve the desired results, and the resulting expansion of the rivet in returning to normal temperature produces only a limited but ineffectual tightening of the frictional engagement between the rivet shank and the side walls of the openings.

20 Another attempt, for example, to secure a satisfactory tight engagement was the provision of 25 a rivet of larger dimension than the preformed openings of the articles, which rivet necessarily had to be forced through the openings preparatory to upsetting its head. This method was also 30 a substantial failure in that the rivet was often damaged upon its insertion in the smaller holes and the articles being riveted were often distorted.

35 Other attempted methods, although achieving 40 a limited success, nevertheless have been found to be expensive, complicated and hence commercially impractical.

45 It is, therefore, an object of my invention to provide an improved rivet comprising a tubular portion and a substantially incompressible filler within said tubular portion that is flowable under 50 pressure to effect expansion of the rivet into positive tight engagement with the side walls of the openings of the articles being riveted together.

55

Another object of my invention is to provide an improved rivet having a tubular portion, a closed head at one end of said portion and a pre-formed flange at its other end and a filler within the tubular portion comprising a relatively incompressible material that is flowable under pressure.

A further object is to provide an improved method of applying a hollow tubular rivet to fastening position in two or more articles to be riveted together which comprises expanding the rivet upon the application of upsetting pressure into tight positive engagement with the side walls of the openings of the articles through which the rivet extends.

A still further object of my invention is to provide an improved method of applying a hollow tubular rivet to fastening position in two or more articles to be joined together which comprises substantially filling the rivet with a relatively incompressible filler that is flowable under pressure, inserting the filled rivet through the articles to be riveted, applying relative pressure to both ends of said rivet to upset one or both of said ends into fastening position and confining said filler within the tubular portion during the application of said upsetting pressure, so as to expand the tubular portion of the rivet into tight positive engagement with the side walls of the openings of the articles through which the rivet extends.

Still another object is to provide an inexpensive seamless, tubular sheet metal rivet that may be quickly and easily applied at normal temperatures to articles to be joined together by the use of any of the present well-known riveting or upsetting means so that a tight positive engagement between the rivet and the side walls of the openings of the articles being riveted may be effected.

Another object is to provide an improved method of applying a hollow tubular rivet having a tubular portion, a closed head at one end of said portion and a preformed flange at its open end, to articles to be riveted together, which comprises first filling the rivet with a relatively incompressible filler, such as soap, grease or other material of similar consistency that is flowable under pressure, inserting the filled rivet through the preformed openings of articles to be riveted together, then placing the flanged end of the rivet against a supporting surface to close the open end thereof and confine the filler within the rivet, then applying a compressive force vertically of said rivet to upset the closed end thereof and to expand the tubular portion outwardly into a tight positive engagement with the side walls of the openings of said articles, and finally, if desired, removing the filler material from the rivet.

Other and further objects and advantages will become apparent as this description progresses, reference being had to the accompanying drawing, in which:

Figure 1 is a vertical sectional view of my improved hollow tubular rivet in unfilled condition:

Fig. 2 is a substantially diagrammatic and vertical cross-sectional view illustrating two of my improved rivets being carried by a belt during the operation of loading the rivet with the flowable filler;

Fig. 3 is a vertical sectional view of my improved rivet containing the flowable filler and ready for use;

Fig. 4 is a vertical sectional view of my improved rivet inserted through the preformed openings of two sheets of material to be united;

Fig. 5 is a vertical sectional view illustrating the

rivet in position between pressure applying means;

Fig. 6 is a vertical sectional view illustrating the rivet in upset position between the pressure applying means; and

Fig. 7 is a rather diagrammatic and vertical cross-sectional view illustrating the upset rivet being passed over a source of heat to remove the flowable filler therefrom.

The improved rivet illustrated in the drawing may be stamped from thin sheets of any one of many well-known kinds of metal such as aluminum, steel, copper, tin, magnesium and other metals and alloys suitable for riveting purposes. The rivet is seamless and has relatively thin walls. It is substantially circular and comprises a vertical tubular portion 10, a closed end or head portion 11 at its upper end and an outwardly extending annular flange 12 at its lower open end. The walls of the rivet head 11 where they join with the vertical portion 10 are rounded as indicated by the numeral 13. The rivet is of such construction that its upper portion including the head 11 with its rounded portion 13 and the upper end of the tubular portion 10 may be collapsed or upset in the manner to be described hereinafter and as shown in Fig. 6. The walls of the tubular portion 10 are also of such construction that they may be expanded outwardly by the application of expanding pressures against the inner surfaces thereof by a manner also to be described more fully hereinafter.

After the rivet has been stamped in the form and construction shown in Fig. 1 and described above, it is then substantially filled with a relatively incompressible filler material, such as soap, grease, any jelly-like or plastic substance of similar consistency, or any other material or substance that is readily flowable under pressure. Any one of a great number of substances may be suitable as the filler. Preferably, the filler material should be of such a consistency and character that it may be readily placed within the hollow cavity 14 of the rivet and retained therein without the provision of additional means during handling or shipment of the rivet even though the rivet be placed open end down as shown in Fig. 3. The filler 15 may be inserted within the rivet cavity 14 manually or automatically by machine in the event mass production of the rivet is desired.

One form of mass production or filling of the rivet with the flowable material is illustrated somewhat diagrammatically in Fig. 2 of the drawing wherein the rivets 16 and 17 are carried by an intermittently movable belt 18 in inverted position, as compared to the position of the rivet shown in Fig. 1, with their open ends up and extending downwardly through openings 19 in the belt 18. The rivets 16 and 17 are supported from the belt 18 by their annular flanges 12. The belt is operated by a suitable mechanism (not shown) for intermittent movement and passes under a feed mechanism 20 from which a suitable filler material 15 in a hot liquid state may be intermittently fed in a predetermined quantity into each rivet as the rivet is momentarily stopped in feeding position directly below the feeding mechanism 20. As shown in Fig. 2, the rivet 17, supported on the belt 18 which moves toward the right, has already been filled with the filler material which has already begun to cool, while the rivet 16 in the left hand side of Fig. 2 is under the feed mechanism 20 and is in the process of being filled with the filler in its hot liquid state.

The belt 18 may be of such a size and length that the filled rivets 16 and 17 may be carried a

sufficient distance thereby to enable the filler material to cool sufficiently so as to assume its jelly-like or normal semi-solid consistency. The cooling of the filler may be hastened by passing the belt 18 and the rivets 16 and 17 through a special cooling zone (not shown). When the filler 15 has cooled to its normal semi-solid consistency at which it is still flowable under pressure, the rivets may be removed from the belt by appropriate means (not shown) and packed immediately for shipment, since at this time the rivets may be turned over to the open side down position shown in Fig. 3, or handled in any manner, without the provision of additional means to prevent the filler 15 from falling out or becoming dislodged from the cavity 14. My improved rivet, therefore, lends itself readily to commercial production, sale and shipment to the users thereof.

After the rivet has been filled with the flowable filler 15, it may then be inserted upwardly through aligned, preformed openings 22 and 23 of two members 24 and 25 which are desired to be riveted together. It is to be noted, however, that in practicing my improved method the flowable filler may be placed within the cavity 14 of the rivet either before or after the rivet has been inserted through the preformed openings 22 and 23. The outside diameter of the tubular portion 10 of the rivet is less than the diameters of the openings 22 and 23 in order that the rivet may be readily inserted in the openings 22 and 23 without damage to the rivet itself or to the members 24 and 25. This difference in diameters is indicated clearly in Figs. 4 and 5 by the small space that exists between the rivet and the vertical walls of the openings 22 and 23. It was the existence of this small space after the rivet had been upset to fastening position that partially caused the undesirable loose unions and permitted relative movement between two riveted articles where rivets of the old types were applied by the old well-known methods. As will be described hereinafter, this space is entirely eliminated with the use of the present rivet applied by the present improved method with the result that a tight positive engagement is achieved between the tubular portion 10 and the vertical walls of the openings 22 and 23.

After the rivet has been inserted in the openings 22 and 23, it may then be placed, as a further step in my improved process of riveting and as illustrated in Fig. 5, against a substantially flat upper surface of a relatively immovable support member 27 with the under surfaces of the rivet flange 12 in engagement therewith. During the upsetting operation the support member 27 serves to support the rivet against withdrawal from the openings 22 and 23 and to close the open end of the rivet to prevent leakage of the filler 15 therefrom under pressure.

In Fig. 6 of the drawing, the next step of my improved process is shown. A movable upsetting means 28, shown diagrammatically and in raised or removed position in Fig. 5 and which may take the form of any of the well-known rivet upsetting means, has been depressed with relatively great pressure against the head portion 11 of the rivet so as to collapse and upset the head portion and form a substantially flat annular retaining head flange 29. Upon collapse of the upper portion 11 of the rivet, the filler 15 therein, being flowable under pressure, is displaced therefrom and the relatively great upsetting pressure applied by the pressure member 28 is transmitted by the flow-

able filler and universally applied against the inner surfaces of the tubular portion 10 with the result that the walls of the tubular portion 10 are expanded outwardly into a very tight and positive engagement with the vertical side walls of the openings 22 and 23. By this expansion the space resulting from the differences in diameter between the tubular portion 10 of the rivet and the openings 22 and 23 of the members 24 and 25 is completely eliminated as are all the disadvantages resulting from its existence.

In addition to serving as a pressure transmitting medium for expanding the tubular portion 10, the flowable filler 15 also enables the rivet head 11 to be turned over or be upset properly in a flat, uniform manner. The upset annular retaining flange 29 formed by the present method is of substantially uniform radial dimension throughout its entire circumferential extent and the entire head is flat, unwrinkled and undistorted. The flowable filler 15 successfully resists collapse, distortion or depression of the head 11 at its center where such tendency is greatest during the upsetting operation. The elimination of such depression and distortion of the head prevents the collection of dirt, decreases wind resistance, and prevents the creation of air eddies, which are considerations of prime importance in aircraft construction.

20 A final, but sometimes unnecessary step in the improved process depending upon the type of work being done and the different considerations involved, is the removal of the filler 15 from the rivet after the head has been upset. The removal of the filler 15 is particularly desirable where reduction of weight is a consideration. This removal may be accomplished by hand with the use of simple tools or by the application of heat, if the filler is one which may be liquified 25 by heat, as shown somewhat diagrammatically in Fig. 7, wherein the rivet in upset position is passed over a source of heat 30, or through a heating zone, in order to reduce the filler 15 to a liquid state and permit it to run out of the rivet cavity 14.

25 In many instances, where weight of the structure being riveted is not an important factor, the filler may be permitted to remain in the rivet. In other instances where use of the riveted structure requires that the cavities 14 be filled so as to present a relatively smooth surface on the underside of the rivet, a plastic material that is flowable under pressure and which will harden or set at normal room temperatures or by the application of heat may be employed with satisfactory results.

30 It will be understood that my invention is not limited to the precise details of construction and operation described with reference to the drawing, and that modifications of form of the rivet may be made, various types of filler materials that are relatively incompressible and flowable under pressure may be used, and various means of performing the steps of the process may be employed, without departing from the spirit and scope of my invention as defined in the appended claim.

I claim:

35 The process of applying in fastening position to parts to be fastened together a hollow rivet comprising a tubular body having an opening at one end and thin collapsible side walls at its other end portion projecting beyond the parts to be fastened and a closed head integrally formed with said thin side walls, which process

comprises the steps of substantially filling the interior space of the hollow rivet with a substantially incompressible filler that is flowable under pressure so that the filler is in engagement with the interior faces of the tubular body and the thin side walls and head thereof, closing the open end of the rivet to prevent escape of the filler under pressure, applying axial pressure against the outer surface of the closed head, transmitting said pressure against the inner faces of the tubular shank and the thin walled portion thereof by means of said filler to expand said tubular shank outwardly into engagement with the parts

being fastened together and to effect collapse of the thin-walled shank portion radially outwardly as the head moves in an axial direction under said axial pressure, and preventing distortion and collapse of said head in an axially inward direction by means of said filler upon application of said axial pressure to the outer surface of said head, whereby a substantially smooth-surfaced retaining element of greater diameter than the tubular shank is formed in fastening engagement with one of the parts being fastened.

HAROLD C. SUNDSTROM.
